UNITED STATES PATENT OFFICE.

ALEX KEARNEY, OF ROANOKE, VIRGINIA, ASSIGNOR TO UNION RAILWAY EQUIPMENT COMPANY, OF CHICAGO, ILLINOIS, A CORPORATION OF ILLINOIS.

DROP BRAKE SHAFT AND MOUNTING THEREFOR.

Application filed June 16, 1927. Serial No. 199,288.

This invention relates to a drop brake shaft of the character employed on flat cars and drop end gondolas where it is desirable to have a hand brake which can be moved out 5 of the way when loading or unloading long materials which project up to or beyond the ends of the car or when using plows, scoops, clam-shell buckets, or the like, or, in general, under circumstances in which the normal 10 elevation of the brake shaft would interfere with the use of the car for the intended purpose, or subject the shaft to danger or injury.

More particularly, the invention relates to 15 the mounting for the lower end of the brake shaft, and to the means provided for supporting the lower end of the shaft when in elevated position, which means are adjustable to permit of the dropping down of the 20 shaft when it is desirable to lower the same to the car floor level.

Further objects and details will appear 25 from the description of the invention in conjunction with the accompanying drawings, wherein—

Figure 1 is a side elevation of the drop shaft and mounting and showing the front cross sill of the car in section;

Fig. 2 is a front elevation of the structure;

Fig. 3 is a sectional plan view taken on line 3—3 of Fig. 2; and

Fig. 4 is a sectional detail showing the 35 adjustable stop of the lower end of the shaft.

The drop brake shaft 10 carries a hand wheel 11 at its upper end. The shaft is preferably square in cross section and is slideable through a pinion 12 meshing with a 40 large spur gear 13 mounted upon a winding drum shaft 14 adapted to wind up the brake chain 15, the forward end of which is attached between lugs 16 depending from the web of the spur gear 13. The details relating 45 to the mounting for the brake chain, however, form no part of the present invention and need not be further described in detail.

The pinion 12 is mounted within a protuberant upper housing 17 which is integrally formed with and projects outwardly from a mounting 18, comprising a curved front wall 19 which merges into a top plate 20 which is riveted to the front cross sill

of the car by means of rivets 21 and 22. As 55 shown, the front sill is composed of two sections 23 and 23^a in overlapping relation, although any other arrangement might be employed.

The curved front wall 19 has depending 60 therefrom a pair of hangers 24 and 24^a in spaced relation to one another, and the inner edges of the hangers are carried inwardly to merge with a box-like lower housing 25 which forms a continuation of the upper protuberant housing 17. The lower ends of 65 hangers 24 and 24^a are turned inwardly and integrally connected with a circular base plate 26 provided in its center with a bore 27 through which extends the winding drum 70 shaft 14 which carries the gear 13.

The base plate 26 is reinforced by means of a gusset plate 28 which, as shown, is of tapering formation comprising a flat end portion 29, an offset intermediate portion 75 30, and an upper connecting portion 31, which latter is riveted to the longitudinally extending draft sill 32, or any other suitable portion of the car frame-work. The formation of the gusset will depend upon the levels in the car frame-work, and the gusset as a whole may be flat or offset to any degree to conform to the requirements of the car structure.

The shaft 14 also extends freely through 85 the gusset and is supported on a removable cross plate 33 which, when removed, will allow the shaft 14 to drop vertically to disengage from the spur gear and permit disassembly of the parts. The plate 26 and 90 end portion 29 of the gusset are connected by rivets 34, 35, 36 and 37, and the rivets 35 and 37 additionally serve to connect the cross plate 33.

The drop shaft 10 is slidably entered 95 through a cap plate 38 which bears upon the upper margins of the protuberant housing 17 and is journaled through a cross wall 39 (see Fig. 4), and the lower end of the shaft bears against the rounded upper end 40 of 100 a gate stop member 41 which, when in supporting position, extends obliquely across the lower housing box 25 and bears against the rear wall 42 thereof, so that it will afford a thrust bearing for the lower end of 105 the shaft.

The gate stop 41 terminates at its forward end in a foot 43 which projects outwardly in

oblique relation to a slot 44 in the front wall of the lower housing 25. The gate stop is provided on its side with trunnions 45 which are carried within U-shaped flanges 46 formed on the inner faces of the side walls of the lower housing, and in alignment with vertically elongated slots or openings 47 in the side walls, which permit of access to the trunnions to provide for the removal of any accumulation of rust or dirt which might interfere with the swinging of the stop gate from the normal oblique position indicated in full lines in Fig. 4 to the vertical position indicated in dotted lines. The slot 44 is carried around the lower front corner of the box housing so as to afford the necessary clearance for the swinging movements of the foot 43.

The drop shaft 10 is additionally guided, journaled and supported by means of a journal bracket 48 suitably secured to the front car sill at a point above the housing 17. Above this journal bracket is located a ratchet wheel 49 on the shaft which is engaged by a dog 50 pivoted on a pin 51 entered through ears 52. The rear or outer end 53 of the dog is adapted to be engaged by a weighted handle 54 pivoted at its inner end to a pin 55, the arrangement being such that the weight of the handle will normally hold the dog in engagement with the ratchet save when the weighted handle is lifted to release the rear end of the dog which will permit the front end to fall out of engagement with the ratchet teeth. The details of the ratchet arrangement, however, form no part of the present invention and need not be further described.

In use with the stop gate in its normal oblique position, its rounded end 40 will furnish a bearing surface for the lower end of the shaft, and by disposing the stop gate in the oblique position indicated, it will be unnecessary to provide any form of ledge or shoulder for supporting the end of the gate which bears directly upon the inner face of the wall 42. With the parts thus normally disposed, it will require but a slight lifting of the shaft to afford the necessary clearance to permit the gate to be swung back into the vertical position indicated in dotted lines. In this respect, the arrangement is distinctly superior to one in which the normal position of the gate is in right transverse relation to the shaft which necessitates a much wider range of swinging movement in order to effect a clearance.

With the gate swung back to releasing position, the shaft may be dropped through an aperture 56 in the bottom wall of the lower housing 25, which is so disposed that the shaft, when thus dropped, will clear the hangers 24 and 24¹ of the gear mounting. Although, as shown, the shaft and the housing through which it operates are located off

center with respect to the longitudinal axis of the mounting, it is obvious that the upper and lower housings for the shafts might be located in the medial position instead of at one side thereof without any substantial modification of structure which would effect the operation of the parts. By locating the shaft to one side of the medial position, however, a slight gain is made in compactness, since the parts will not project forwardly to quite the same degree as in the case where the medial position is employed.

I claim:

1. In mechanism of the class described, the combination of a vertically disposed shaft, a housing through which the shaft is slidably mounted, gear elements actuated by the shaft, and a stop gate pivotally mounted within the housing and normally occupying an oblique relation with respect to the axis of the shaft and having its free end in abutting relation to the face of the side wall of the housing at a point distant from and substantially above the pivotal mounting for the gate, said gate being positioned to be swung back from its shaft engaging position to permit the shaft to clear the gate, substantially as described.

2. In mechanism of the class described, the combination of a vertically disposed shaft, a housing through which the shaft is slidably mounted, gear elements actuated by the shaft, and a stop gate pivotally mounted within the housing and normally occupying an oblique relation with respect to the axis of the shaft and having its free end in abutting relation to the face of the side wall of the housing at a point distant from and substantially above the pivotal mounting for the gate, said gate being positioned to be swung back from its shaft engaging position to permit the shaft to clear the gate, the gate being provided with a foot extending outwardly through the housing in opposed relation to the shaft engaging portion of the foot to afford means for swinging the gate, substantially as described.

3. In mechanism of the class described, the combination of a mounting comprising a main portion adapted for connection to the framing of a car, a spur gear and brake connections mounted within the main portion of the mounting, a housing forwardly protruding from the main portion of the housing, a pinion mounted within the upper portion of said housing, a shaft slidably mounted through the pinion and through the housing and adapted when lowered to extend below the housing, a swinging gate pivotally mounted within the housing and normally occupying an oblique relation to the axis of the shaft and having its free end in abutting relation to the inner face of the rear side wall of the housing, at a point substantially above the pivotal axis, and means for swing-

115

ing the gate upwardly to clear the shaft and permit the dropping of the shaft, substantially as described.

4. In mechanism of the class described, the combination of a mounting comprising a main portion adapted for connection to the framing of a car, a spur gear and brake connections mounted within the main portion of the mounting, a housing forwardly protruding from the main portion of the mounting, a pinion mounted within the upper portion of said housing, a shaft slidably mounted through the pinion and through the housing and adapted when lowered to extend below the housing, a swinging gate located within the housing and provided with laterally extending trunnions near its forward end, U-shaped flange sockets on opposite walls of the housing for journaling the trunnions, the gate being of a length when in obliquely disposed relation to the axis of the shaft to bring its free end into abutment with the rear side wall of the housing at a point substantially above the pivotal axis, and means for swinging the gate upwardly to release the shaft and permit the dropping of the latter, said means being in the form of a forwardly and downwardly extending foot projecting outwardly from the housing, substantially as described.
5. In mechanism of the class described, the combination of a mounting comprising a main portion adapted for connection to the framing of a car, a spur gear and brake connections mounted within the main portion of the mounting, a housing forwardly protruding from the main portion of the mounting, a pinion mounted within the upper portion of said housing, a shaft slidably mounted through the pinion and through the housing and adapted when lowered to extend below the housing, a swinging gate located within the housing and provided with laterally extending trunnions near its forward end, U-shaped flange sockets on opposite walls of the housing for journaling the trunnions, the gate being of a length when in obliquely disposed relation to the axis of the shaft to bring its free end into abutment with the rear side wall of the housing at a point substantially above the pivotal axis, and means for swinging the gate upwardly to release the shaft and permit the dropping of the latter, said means being in the form of a forwardly and downwardly extending foot projecting outwardly from the housing, substantially as described.
6. In mechanism of the class described, the combination of a mounting comprising a main portion adapted for connection to the framing of a car, a spur gear and brake connections mounted within the main portion of the mounting, a housing forwardly protruding from the main portion of the mounting, a pinion mounted within the upper portion of said housing, a shaft slidably mounted through the pinion and through the housing and adapted when lowered to extend below the housing, a swinging gate located within the housing and provided with laterally extending trunnions near its forward end, U-shaped flange sockets on opposite walls of the housing for journaling the trunnions, the gate being of a length when in obliquely disposed relation to the axis of the shaft to bring its free end into abutment with the rear side wall of the housing at a point substantially above the pivotal axis, and means for swinging the gate upwardly to release the shaft and permit the dropping of the latter, said means being in the form of a forwardly and downwardly extending foot projecting outwardly from the housing, substantially as described.
7. In mechanism of the class described, the combination of a mounting comprising a main portion adapted for connection to the framing of a car, a spur gear and brake connections mounted within the main portion of the mounting, a housing forwardly protruding from the main portion of the mounting, a pinion mounted within the upper portion of said housing, a shaft slidably mounted through the pinion and through the housing and adapted when lowered to extend below the housing, a swinging gate located within the housing and provided with laterally extending trunnions near its forward end, U-shaped flange sockets on opposite walls of the housing for journaling the trunnions, the gate being of a length when in obliquely disposed relation to the axis of the shaft to bring its free end into abutment with the rear side wall of the housing at a point substantially above the pivotal axis, and means for swinging the gate upwardly to release the shaft and permit the dropping of the latter, said means being in the form of a forwardly and downwardly extending foot projecting outwardly from the housing, substantially as described.

ALEX KEARNEY.
